(No Model.)

C. W. PATTON.

CHURN.

No. 324,879.

Patented Aug. 25, 1885.

UNITED STATES PATENT OFFICE.

CHARLES W. PATTON, OF CHICAGO, ILLINOIS.

CHURN.

SPECIFICATION forming part of Letters Patent No. 324,879, dated August 25, 1885.

Application filed June 27, 1884. (No model.)

To all whom it may concern:

Be it known that I, CHARLES W. PATTON, a citizen of the United States, residing at Chicago, in the county of Cook and State of Illinois, have invented certain new and useful Improvements in Churn-Powers, of which the following is a specification, reference being had therein to the accompanying drawings.

This invention has relation to improvements in churn-power mechanism; and it consists in the construction and novel arrangement of devices, as will be hereinafter more fully set forth, and particularly pointed out in the claim appended.

15 In the accompanying drawings, in which similar letters of reference indicate corresponding parts in the figures, Figure 1 is a perspective view of my invention, and Fig. 2 is an enlarged sectional detail view.

20 In the said drawings, A indicates the base, which is sufficiently broad to form a substantial brace for the churn-operating mechanism and a receptacle for the churn-body.

B indicates the upright carrying the operating mechanism. This upright is firmly secured at its lower end to the base-block A, and inclines upwardly and forwardly, or in the direction of the churn-body, so that the dasher guide-arms may overhang the churn, (the same being of tapering form,) and the dasher-rod brought truly above the churn without necessitating the use of long and clumsy guide-arms. The post also tapers upwardly from base to top.

35 C C indicate the dasher guide-arms, which are secured to the upright and extend laterally therefrom to partially overhang the churn. These arms are provided with vertical slots a for the passage of the dasher-rod, the branches

40 b of which are transversely perforated, as shown, to receive the transverse pins c, for holding the said rod in the slots of the guide-arms.

D indicates the drive-wheel shaft, which is 45 provided at its forward end with the drive-wheel E, having one of its spokes provided

with a plurality of perforations, e, to receive one of the hooked ends of the pitman-rod F, for adjusting the stroke of the dasher, and at its rear end with a fixed vertical pinion, g, which 50 engages a vertical gear-wheel, G, mounted in the upright, and carrying a crank-arm for turning the same. This shaft D is inclosed in a tube, h, which extends transversely through the upright, and has on its upper longitudinal side a lubricant-receptacle, H.

The apertures in the upright may be threaded, and the inner ends of the dasher guide-arms also threaded for insertion into the upright.

From the foregoing description, taken in connection with the accompanying drawings, the operation and advantages of my invention will be obvious.

I am aware that it is not new to provide a conical sheet-metal frame for supporting a 65 churn-operating mechanism, and that it is also old to provide guide-arms for the dasher rod with open slots, and therefore do not claim such devices, broadly; but,

Having thus described my invention, what 70 I claim as new, and desire to secure by Letters Patent, is—

The device herein described, consisting of the flat base A, the tapering upright B, inclined as described, and provided with the 75 guide-arm apertures, the detachable guide-arms c, having the vertical open slots a, and the transverse pins for locking the dasher in the said slots, the horizontal shaft carrying at one end the pinion g and at the opposite end 80 the drive-wheel E, the tube h, surrounding the said shaft and provided with the lubricant-receptacle H, and the pitman and gear-wheel carrying the crank-arm, substantially as specified.

85 In testimony whereof I affix my signature in presence of two witnesses.

CHARLES W. PATTON.

Witnesses:

GEORGE A. ROSE,

CHARLES S. QUINLAN.
